DRILL ROD RACK

Otto Wiegel, Chicago, Ill.

Application September 6, 1945, Serial No. 614,773

6 Claims. (Cl. 211—87)

1

The storage of stocks of long straight rods of small diameter, classified according to their transverse dimensions and protected against injury, has presented considerable difficulty and is usually accomplished by providing a series of adjacent box-like bins with straight vertical walls for holding the bars in horizontal disposition. Such arrangements are subject to many disadvantages, among which are the difficulty of picking the individual rods from a horizontally disposed box-like bin and the difficulty of caring for and enabling the ready selection of rods of less than a standard length.

The main objects of this invention are to provide an improved form of storage rack for supporting slender rods, such as drill rod stock, in vertical position and in an arrangement whereby rods of one diameter may be kept separate from those of another diameter and whereby the entire stock may be kept properly classified in progressive arrangement according to size, so that any rod of specific dimensions can be readily selected at a glance; and to provide a rack of this kind which may be light in weight but capable of sustaining a comparatively heavy load.

A specific embodiment of this invention is illustrated in the accompanying drawings in which:

Figure 1 is an isometric perspective view of a rack designed to hold in graded relation a quantity of drill rod stock, comprising an equal number of each size of the rods.

Fig. 2 is a developmental plan view of one of the shelf elements of the rack of Fig. 1.

In the form shown, the rack structure is arranged to be hung against a wall and comprises two or more vertical bars 1 having hanger apertures 2 at their upper ends and having struck out from their bodies a plurality of forwardly and upwardly inclined tongues 3 for the purpose of wedgingly supporting a series of horizontally disposed shelves.

Each of the shelves, except the lowermost one which serves as a bottom support on which the rods rest, comprises an elongated plate 4 having therein a series of perforations 5, of progressively reduced areas, arranged in a series from one end of the shelf to the other. Each of the apertures 5 is of similar pentagonal form, pointed at its front end 6, and its side edges 7 diverge rearwardly and then become substantially parallel with each other. The progressive reduction of the areas of the apertures, so as to hold like quantities respectively of the graded sizes of rods, is accomplished as shown in Fig. 2 by making the shelf from a tapered plate and punching the

2

apertures 5 in a series so that their pointed front ends 6 are equally spaced from the front edge 8 of the plate and so that their side edges extend to the rear edge 9 of the plate.

5 A front stiffening flange 10 is formed by bending the plate along the longitudinal line 11 of Fig. 2, which line is parallel with the front edge 8 of the plate and located between that edge and the pointed ends 6 of the apertures.

10 Each shelf is reinforced at its rear edge by an angle bar having a vertical leg 12 and a horizontal leg 13, the horizontal leg being spot-welded to the web portions 14 of the plate 4 between the apertures 5. The horizontal leg or flange 13 15 serves as a rear support for the rod bundles in each aperture 5.

The vertical legs 12 of these reinforcing bars are perforated at 15 to provide suitable apertures for receiving the tongues 3 of the hanger bars 1.

20 The number of such hanger bars 1 required is, of course, relative to the length and beam strength of the bottom shelf and the distribution of weight over the same. Likewise, the number and spacing of the upper shelves is dependent upon the standard length of the stock rods that are to be provided for and the need for intermediate supports for the slender rods and for rods of less than the standard length.

25 The weight of the rods is carried by the base plate 16 on which the lower ends of the bars rest and this plate is preferably not perforated at least in those parts thereof with which the rods have contact. This plate forms the bottom part of a rigid hollow beam comprising one of the shelves 4 which forms the top of the beam, a rear wall 17 and a front wall 18. The rear wall 17 has a top flange 19 that overlays the shelf plate 4 and is spot-welded thereto at points between the apertures 5.

30 40 The front wall 18 has lips 20 struck out of it so as to extend inwardly to wedgingly grip the depending flange 10 of the top plate 4 and the upstanding flange 21 of the bottom plate 16.

45 A perforated plate 4,1 corresponding in form with the shelf plates 4 but having its front flange 10,1 bent upwardly is spot-welded to the front plate 18 so as to be housed in the interior of the box-like structure where it serves to keep in proper vertical disposition any short bars that 50 may be inserted into the apertures 5 and be of insufficient length to be supported by an upper shelf.

The angle between the front and rear edges of the plates 4 is determined by the size of the bars that are to be stored in the first and last

apertures of the series so that each of these apertures will hold and approximately define a bundle comprising a like number of its respective size of rods, and since the stock of drill rods is uniformly graded throughout the whole series, this expedient insures that each of the apertures in the entire series will support substantially a like number of its respective size of rods.

The front plate 18 carries numerical characters 22 as indicia identifying the stock in the respective apertures, according to its customary trade numerical designation and also carries another series of numerals 23 which give the decimal dimensions of the respective rod diameter.

When one of the apertures is completely filled with rods supported vertically in the rack, there will be a single rod standing out in front of the others, where it can be readily gripped by the fingers of the person who is about to remove it from the rack; and when the aperture is only partly filled with rods, there is a tendency for them to slip, one over another to bring one to the front when the group is gripped between the thumb and fingers of the person's hand.

Although but one specific embodiment of this invention is herein shown and described, it will be understood that numerous details of the structure shown may be altered or omitted without departing from the spirit of the invention as defined by the following claims.

I claim:

1. In a rod rack, a shelf plate uniformly tapered in width from end to end and having therein a longitudinal series of spaced apertures of like-tapered form with respect to an axis transverse to the plate, the narrow ends of such apertures being uniformly spaced inward from the front edge of said plate and the sides of said apertures extending to the rear edge of the plate, whereby the apertures of the series are graded as to areas by the slant of the rear edge of the plate, and a vertically disposed rear panel having a flange overlapping and connected to said plate.

2. In a rod rack, a shelf plate uniformly tapered in width from end to end and having therein a longitudinal series of spaced apertures of like-tapered form with respect to an axis transverse to the plate, the narrow ends of such apertures being uniformly spaced inward from the front edge of said plate and the sides of said apertures extending to the rear edge of the plate, whereby the apertures of the series are graded as to areas by the slant of the rear edge of the plate, a vertically disposed rear panel having a top flange overlapping and connected to said plate, and a bottom panel extending horizontally across the vertically projected areas of said apertures.

3. In a rod rack, the combination as a unitary structure of a shelf plate uniformly tapered in width from end to end and having therein a longitudinal series of spaced apertures of like-tapered form with respect to an axis transverse to the plate, the narrow ends of such apertures being uniformly spaced inward from the front edge of said plate and the sides of said apertures extending to the rear edge of the plate, whereby the apertures of the series are graded as to areas by the slant of the rear edge of the plate, a verti-

cally disposed rear panel having a top flange overlapping and connected to said plate, a bottom panel extending horizontally across the vertically projected areas of said apertures, vertical flanges

5 on the front edges of said plate and bottom panel, a front plate supported by said panels, and an internal shelf plate extending across the interior of said structure between said front plate and rear panel and having rod apertures corresponding to and aligned with the apertures in said shelf plate.

10 4. In a rod rack, a shelf plate having therein a longitudinal series of spaced apertures of like tapered form with respect to an axis transverse to the plate, the front ends of said apertures being uniformly spaced from the front edge of said plate and sides of said apertures extending toward the rear edge of the plate, and a bar extending along and attached to the rear edge of said plate and partly overlapping said apertures,

20 the front edge of said bar being inclined with respect to the front edge of said plate, whereby the apertures of the series are graded as to areas by the slant of said bar.

25 5. In a rod rack, a shelf plate having therein a longitudinal series of spaced apertures of like tapered form and elongated with respect to an axis transverse to the plate, the front ends of said apertures being uniformly spaced inward from the front edge of said plate and the sides of the apertures extending to the rear edge of said plate, and a bar extending along and attached to the rear edge of said plate and partly overlapping said apertures, the front edge of said bar being inclined with respect to the front edge of said

30 plate, whereby the apertures of the series are graded as to areas by the slant on the front edge of said bar.

35 6. In a rod rack, a shelf plate uniformly tapered in width from end to end and having therein a longitudinal series of spaced apertures of like tapered form with respect to an axis transverse to the plate, the narrow ends of said apertures being uniformly spaced inward from the front edge of said plate and the sides of said apertures diverging rearwardly and extending to the rear edge of the plate, and a bar of uniform width attached to the rear edge of said plate and overlapping said apertures to provide a rearward support for the rods therein, whereby the apertures of the

40 50 series are graded as to areas by the slant of said bar.
